UNITED STATES PATENT OFFICE.

JEROME BARTOLOWSKY, OF OAKLAND, CALIFORNIA.

DESIGN FOR A TOY WHISTLE.

59,323.

Specification for Design.

Patented Oct. 11, 1921.

Application filed April 25, 1921. Serial No. 464,453. Term of patent 14 years.

To all whom it may concern:

Be it known that I, JEROME BARTOLOWSKY, a citizen of Germany, residing at Oakland, in the county of Alameda and State of California, have invented a new, original, and ornamental Design for Toy Whistles, of which the following is a specification, reference being had to the accompanying drawing, forming part thereof.

Figure 1 is a front view of a toy whistle, showing my new design.

Fig. 2 is a side view of same.

Fig. 3 is a rear end elevation of same.

I claim:

The ornamental design for a toy whistle, as shown.

In testimony whereof I affix my signature.

JEROME BARTOLOWSKY.
